UNITED STATES PATENT OFFICE.

ROMAN G. KISSEL, OF DE KALB, ILLINOIS.

MOLDER'S-SAND-CUTTING MACHINE.

1,084,450.

Specification of Letters Patent. Patented Jan. 13, 1914.

Application filed June 14, 1913. Serial No. 773,796.

To all whom it may concern:

Be it known that I, ROMAN G. KISSEL, a citizen of the United States, residing at De Kalb, in the county of Dekalb and State of Illinois, have invented a new and useful Improvement in Molders' Sand-Cutting Machines, of which the following is a specification.

The sand used for molding in foundries becomes strewn over the floor, and it is customary to gather it into a pile, from which it is taken for use, by shoveling it by hand, which is a laborious and expensive operation.

The object of my invention is to provide a machine for gathering or "cutting" this sand, thereby to facilitate and expedite handling it in the operation of molding in foundries, and render the work more economical in time and labor.

In the accompanying drawings, Figure 1 shows my molder's-sand cutting-machine by a view in side elevation; Fig. 2 is a top plan view of the machine; Fig. 3 is a view of the same in rear elevation; Fig. 4 is a view in elevation of one side of the frame, and Fig. 5 is a section on line 5, Fig. 2.

The carriage-frame of the machine consists of two side-members 6 and 7, each having depending centrally from it a yoke 8, the side-members being rigidly connected together by a tie-bar 9 extending between the yokes at their lower ends. The end-posts of each side-member are provided on their ends with axle-bearings 10, 11, 12 and 13, while on the member 7 adjacent to its rear post is formed a laterally-outward extending sleeve-bearing 14. In the lower bearings 11 and 13 are supported, respectively, the axles 15 and 16 carrying on their ends the carriage-wheels 17. A crank-shaft 18 is journaled at its ends in the frame-bearings 10, and a similar crank-shaft 18' is journaled at its ends in the frame-bearings 12, each of these shafts being formed with four elongated cranks. Link-bars 19 pivotally connect together the corresponding cranks on the two crank-shafts, these bars having bifurcated ends formed with segmental rack-heads 20. In the bifurcated end of each bar 19 is pivoted at 21, through its straight end, an upwardly-curved handle 22 terminating at its opposite end in a blade-holder 24 and adjustably fastened to the bar by a pin 22' inserted through it and through

coincident holes in the rack 20. Each handle extends through a notch 23' formed in the upper end of an arc-shaped blade 23, which is riveted to the blade-holder. The outer blades are supported on the holders to extend therefrom laterally at an angle of about sixty degrees, more or less, thus protecting the inner edge of each outer blade ahead of its rear edge for the purpose hereinafter explained.

A gear-wheel 25 on a carriage-wheel 17 meshes with an idler 26 journaled in the bearing 14; and this idler meshes with a gear 27 secured on an end of the crank-shaft 18'.

The machine may be dragged over the molding-floor through the medium of a tongue 28, indicated as being pivoted to the axle 15, or by a suitable motor (not shown) which may be carried on the machine and geared to the wheel 26.

In operating the machine by moving it over a foundry-floor, the gear 26 drives the gear 27 to turn the crank-axle 18', thereby turning both crank-axes and, by their bar-connections 19, working the blades to the floor-level to shovel the sand into a pile underneath the machine as it advances. By the angular setting, referred to, of the outer blades, they work the sand to the two middle blades, thereby producing a desirably thorough mixture of the sand and accumulating it into a heap of general triangular shape, as has hitherto been done by hand.

Preparatory to moving the machine about, when not operating, to reduce it to an inoperative condition the shovels are raised on their pivots 21 upon withdrawing the pins 22', and are supported in their raised position by reinserting the pins through proper holes in the racks 20, so that in the working of the blades, they will not reach down to the floor-level or to the sand thereon.

What I claim as new and desire to secure by Letters Patent is—

1. A molder's sand-cutting machine, comprising a wheeled carriage having posts on opposite ends of its frame, crank-shafts journaled on said posts, bars pivotally connecting corresponding cranks of said shafts, gearing connected with one crank-shaft for driving the shafts, and shovels supported on the rear ends of said bars to be operated by the cranks in the forward movement of the machine to actuate the bars to work the

shovels in the direction of said movement over the floor-level, the two outer shovels being set to extend at an angle to the line of draft and sweep the sand on said level 5 into the path of the intermediate shovels.

2. A machine of the character described, comprising a wheeled carriage having posts on opposite ends of its frame, crank-shafts journalized on said posts, bars pivotally connecting corresponding cranks of said shafts, shovels having handles at which they are adjustably connected with the bars at one end thereof, and gearing connected with one crank-shaft for driving the shafts to work 10 the shovels over a floor-level, for the purpose set forth.
- 15 3. A molder's sand-cutting machine, com-

prising a wheeled carriage having posts on opposite ends of its frame carrying on their lower ends the wheel-axes, crank-shafts 20 journalized on the upper ends of the posts to work above the axles, bars pivotally connecting corresponding ends of said shafts, gearing connected with one crank-shaft for driving the shafts, and shovels supported on the rear end of said bars to be operated by the cranks in the forward movement of the machine to actuate the bars to work the shovels in the direction of said movement over the floor-level.

ROMAN G. KISSEL.
